STRAP FASTENER FOR SKI EQUIPMENT

Edward A. Lloyd, Box 158, Glenridge Road,
Scotia, N.Y. 12302

Filed May 2, 1973, Ser. No. 356,523

Term of patent 14 years

Int. Cl. D9—06

U.S. Cl. D9—252

FIG. 1 is a perspective view of a strap fastener for ski equipment showing my new design;

FIG. 2 is a bottom plan view; and

FIG. 3 is a perspective view of the strap fastener for ski equipment shown in an operative condition.

I claim:

The ornamental design for a strap fastener for ski equipment, as shown and described.
